UNITED STATES PATENT OFFICE

2,572,112

SPONGE AND SQUEEGEE CLEANER

Jerome T. Coppe, Chicago, Ill.

Application February 23, 1946, Serial No. 649,473

1 Claim. (Cl. 15—121)

1

This invention relates to a cleaning device and is particularly useful as a cleaner for windows and similar surfaces.

In the cleaning of windows it is extremely difficult and virtually impossible to clean certain window areas without being on the outside of the window. The operation is not only an unpleasant one in cold and disagreeable weather, but it is hazardous when one is obliged to stand outside the window or sit upon the window sill. Further, the top window frame very often sticks and can be moved only with great difficulty.

An object of the present invention is to provide simple means for the cleaning of all of the surfaces of the windows while permitting one to stand inside the room. A further object is to provide a cleaning device which may be manipulated from inside the room for cleaning all of the surfaces of the windows while supplying at the same time means for removing the liquid from the windows and drying the same. A further object of the invention is to provide a cleaning device effective for supplying a washing fluid to window surfaces on the outside of a room while, at the same time, providing means for displacing the liquid from the surface and drying the window surface. Other specific objects and advantages will appear as the specification proceeds.

The invention is illustrated, in a preferred embodiment, by the accompanying drawing, in which—

Figure 1 is a vertical sectional view of a window end in which a cleaning device embodying my invention is employed; Fig. 2, a broken plan view of the sponge and squeegee structure employed with my washing device; Fig. 3, a transverse sectional view, the section being taken as indicated at line 3 of Fig. 3; and Fig. 4, a perspective view of a sponge structure attached to a plate insert.

In the illustration given, 10 designates a handle which may be of metal or other suitable material and which may be equipped with a loop handle 11. The upper end of the handle 10 is offset at 12 and is secured to a metal back strip or plate 13. The plate 13 is turned inwardly and upwardly at its bottom to provide a loop 14 for receiving the sponge plate 15. The upper end of the back plate 13 is provided with a downwardly turned portion 16 which also provides a loop for receiving the plate 15. The metal strip 16 is also turned upwardly again upon itself to form a second loop portion 17 for receiving the squeegee or resilient edge 18.

2

Secured to the insert plate 15 is a sponge body 19 formed of porous rubber or any other suitable absorbent material. An excellent bond between the sponge 19 and plate 15 is provided by rubber cement, but other suitable adhesives may be employed.

The handle 10 may be secured to the back plate 13 by rivets 20 or any other desired means.

In the construction illustrated, it will be noted that the handle 10 is substantially in line with the back plate 13 and that the metal parts thus associated with the sponge 19 and squeegee 18 lie in a relatively narrow longitudinal plane. Thus, it is easy to project the metal structure between small crevices or spaces to permit its use in the interiors between windows, etc. While the sponge 19 and squeegee 18 project slightly, these will be compressed when it is desired to insert the device in a narrow space and thus they form no obstructions to such passage.

The use of the device in connection with the cleaning of windows is illustrated in Fig. 1. In this figure, 21 designates the upper window frame and 22 its pane, and 23 designates the lower window frame, whose pane is designated by the numeral 24. The upper portion 25 of the lower window frame has an inwardly extending sealing portion 26. Similarly, the outer window frame 21 has its lower portion 27 provided with the usual inwardly extending seal 28. When the members 26 and 28 are brought together, as shown, lowering the inner frame 23, the two members provide a substantially air-tight seal between the windows.

In the illustration given in Fig. 1, the upper window 21 is shown in its usual position, but the lower window frame 23 has been raised. When the lower frame 23 is moved to the raised position indicated in Fig. 1, the washing device carried by handle 10 can be readily inserted between the window frames and employed for washing the outer side of the lower window pane, as illustrated. Normally, it is better to have the lower window frame 23 in the raised position indicated in Fig. 1 or, if desired, an even lower position may be maintained and, in such position, the washing device can be easily caused to traverse the entire outer space of the pane 24.

The difficult task in window washing is to clean the outside surface of the lower pane 24 and in order to clean this surface, it is customary to either wash it while standing on the outside or while sitting on the window sill. With the construction shown, one can stand entirely within the room and effectively clean this diffi-

cult surface. Similarly, the outer surface of the upper window can be readily cleaned while one is standing on the floor in the inside of the room. The cleaner employed not only permits one to apply washing fluid to the difficult surface on the interiors of the windows, but also provides means for scrubbing the surface and, after scrubbing, drawing off the water with a resilient edge or squeegee, while at the same time providing a second suction means for absorbing the water which is drawn downwardly by the squeegee. For example, when the sponge 19 is filled with water or washing fluid, it may be moved over the entire outer surface of the pane 24 so as to scrub the surface. After this washing operation, the rigid back 13, under stress imposed by the handle 10, may be urged against the sponge 19 so as to press the water from the sponge. The squeegee is then caused to wring the water from the outer surface of pane 24 and as it does so, a porous pad 19 soaks up the water stream thus produced. The device is, therefore, effective not only as a washing pad, but also as a squeegee and blotter of the water, the rigid back plate 13 serving the useful function of wringing the pad of its moisture when it is desired to use it in the final drying step.

The long handle 10 enables substantial pressure to be applied to the cleaning device at any point upon the window pane and even while the device is within the compartment between the two window panes. It provides a control means for washing the window with the desired pressure on the pad 19 and the further additional pressure for wringing the pad 19 of most of its water to render it effective as a blotter or drying means when the squeegee is serving to wring the water from the pane surface.

The new cleaner is not only built in a compact and aligned arrangement whereby it can be inserted between window frames and manipulated therebetween but also, the cleaning device contains in itself all of the essentials for washing, for removing water from the pane and for soaking up the water thus dislodged. Thus a complete cleaning operation can be brought about by the insertion of the cleaning device but once through the space between window frames.

It will be understood that the cleaner is effective as a means for cleaning floors, walls, cars and other surfaces.

The handle 10, which may be formed of metal or other resilient material and which is provided with a looped handle 11, is found to be very effective as a means for applying pressure upon the sponge even when the sponge is at a remote point. Further, the long shank of the handle enables the handle to be pressed against the por-

tion 28 of the upper window frame so as to use it as a lever for applying pressure toward the pane 24. The handle permits a nice control of the pad 19 so that it can serve as a washing means and further as an effective means for wringing the pad 19 so that it may serve as an absorbent member.

While in the foregoing specification, I have set forth one embodiment of the invention in detail, it will be understood that such details may be varied widely by those skilled in the art without departing from the spirit of my invention.

I claim:

A window pane cleaner, comprising a plate having an outer end portion adapted to hold a squeegee and an inner edge portion opposite said squeegee-holding end, an elongated handle secured to the back of the plate and provided with an offset engaging the inner edge portion of said plate and extending to the rear of said plate in substantially longitudinal alignment therewith, a resilient squeegee secured to the outer end of said plate and with the edge thereof inclined away from said plate and outwardly therefrom, and a sponge body having its rear surface secured to said plate and its front surface aligned with the outer edge portion of said squeegee, said squeegee extending outwardly from said plate so as to yield in a rearward direction when said sponge structure is pressed against a window pane surface to free said sponge of liquid, said squeegee having at its outer tip an edge pointed in cross-section for bearing against the window pane to free the pane of water.
